UNITED STATES PATENT OFFICE.

LOUIS F. GEISSLER, OF PHILADELPHIA, PENNSYLVANIA, ASSIGNOR TO VICTOR TALKING MACHINE COMPANY, A CORPORATION OF NEW JERSEY.

DESIGN FOR A TALKING-MACHINE-RECORD CABINET.

40,399.

Specification for Design.

Patented Dec. 14, 1909.

Application filed October 19, 1909. Serial No. 523,547. Term of patent 14 years.

To all whom it may concern:

Be it known that I, LOUIS F. GEISSLER, a citizen of the United States, and a resident of the city of Philadelphia, county of Philadelphia, State of Pennsylvania, have invented a certain new, original, and ornamental Design for Talking-Machine-Record Cabinets, of which the following is a specification, reference being had to the accompanying drawing, forming a part thereof.

The figure is a perspective elevational view of a cabinet for talking machine records showing my new design.

What I claim is:—

The ornamental design for a cabinet for talking machine records as shown.

LOUIS F. GEISSLER.
